UNITED STATES PATENT OFFICE.

FRANK R. STAFFORD, OF PHILADELPHIA, PENNSYLVANIA.

METHOD OF MAKING DIES.

1,314,612.

Specification of Letters Patent.

Patented Sept. 2, 1919.

Original application filed August 22, 1916, Serial No. 116,346. Divided and this application filed June 13, 1917. Serial No. 174,567.

To all whom it may concern:

Be it known that I, FRANK R. STAFFORD, a citizen of the United States, residing at Philadelphia, in the county of Philadelphia and State of Pennsylvania, have invented 5 certain new and useful Improvements in Methods of Making Dies, of which the following is a specification, reference being had therein to the accompanying drawing.

10 My invention comprehends a novel method of making dies.

Ancillary features of invention and improvement will sufficiently appear from the detailed statement hereinafter.

15 This application is a division of my prior application Serial No. 116,346, filed August 22, 1916.

My invention is illustrated in the accompanying drawings in which

20 Figure 1 is an isometric projection of a pair of master dies for forming a trimming punch.

Fig. 2 represents in side elevation a die punch holder.

25 Fig. 3 represents in side elevation the die punch holder seen in Fig. 2, the views being taken 90° apart.

Fig. 4 represents a transverse section of the punch holder seen in Figs. 2 and 3.

30 Fig. 5 represents a bottom end view of the punch.

Fig. 6 represents a plan view of a die and its holder coöperating with a trimming punch.

35 Fig. 7 represents a section on line 7—7 of Fig. 6.

Fig. 8 represents in perspective one type of an article which may be formed.

40 Figs. 9, 10 and 11, show stages in the formation of the unit die of Figs. 6 and 7.

It will be understood that the article shown in Fig. 8 is selected for purposes of illustration only, and that the shape and proportions of each die may be varied according 45 to its uses, without departing from the invention. The specific form of article and the specific form and arrangement of the set of tools illustrated and described herein, are for drop forging, on hot metal, the par-

but certain operations which will be pointed out, are performed when the metal is cold; and by making slight changes which will be apparent to those skilled in the art, these tools are perfectly applicable to cold stamping, as required in the manufacture of such articles as jewelry, and many others. 55

In Fig. 1, I have shown a pair of drop forging dies 22 and 23, each containing a straight figure having a sectional contour 60 corresponding exactly to the outside contour of the article. These dies are secured in a press in the position shown and operate upon a bar of metal to produce the trimming punch 24 shown in Figs. 2, 3 and 4. 65

Figs. 6 and 7 show a working trimming die. The die proper 25 is carried on a body 26, has beveled sides 27 and is held in place by a clamping plate 28. It has a central opening 29, and its inner walls are first beveled at 30 and then at their upper edges 70 formed with straight sides 31. A punch fits accurately within the edges 31, and in operation is secured above the same in the press.

The die of Figs. 6 and 7 is formed, also in 75 the hydraulic press or equivalent machine. The first blow or operation causes the metal to flow into the shape shown in Fig. 9, the second forms the shape of Fig. 10, and the third clears out the central opening, trims off 80 the outer flash, and forms the central opening with the proper bevel 30 and straight cutting edges 31. The shape as shown in Fig. 11 is then pickled and tumbled to remove the scale left by the hot forging, and 85 is compressed in the hydraulic press between complementary dies shaped to receive it, under heavy pressure, producing absolutely accurate dimensions and shape, and a glass finish. The die is then hardened and its 90 base and top or crown are ground, with or without rehardening, giving the finished tool, ready for clamping onto its body as shown in Fig. 7. The die body of Figs. 6 and 7 is inserted in a groove in the bed plate 95 of the press, and has its opposite edges beveled to fit undercut bevels in said groove. One side of the channel in the press is fitted with a steady-pin 38, and the corresponding side of the beveled edge of the body of the 100

die is notched to fit said pin. There is enough clearance between the opposite edge of the die and the opposite dovetail of the slot to take a key, which is driven in tightly 5 to hold the die in position. When this key is withdrawn, the die may be inserted, pressed over against the pin, and when it is thus centered and steadied by the pin, the tapered key or keys may be inserted from 10 one or both ends of the slot so that the die is not only firmly held in the groove, but is solidly pressed against the pin so that it is accurately and continuously centered.

This die has been described and is indicated in the drawing with its end surface or head plain. I have found it advantageous in some cases to serrate this, so that the edge all around the central opening 29 is fluted or serrated instead of plain. In order to attain 20 this end, the flutings are on radial lines converging approximately to a point at the center of the opening (the die being considered in plan as shown in Fig. 6.) The die, upon which the article rests, while a punch is run through its central opening, is struck up in the same manner as the die shown in Figs. 6 and 7, except that the die has the shape of the article impressed in it, and its edge cut out to form an opening inside the internal contour of the article. This would be difficult to make, as would any of these shapes, in any other manner than by a master punch.

The punch shown in Figs. 2 to 5 inclusive 35 coöperates with the trim die of Figs. 6 and 7, the article being forced through the die by the punch, and the punch being provided not only with the oval body portion 24, but with a lateral projection or tongue 24^a 40 matching a corresponding opening 31^a in the die, to force down the projecting part of the article. (See Fig. 8.) The piercing die, on the other hand, has its inner edges the size and shape of the initial opening in the 45 article, which of course has no projection but is simply oval. All around these edges an intaglio impression of the article is formed, the inner edge being left sharp, and the depth of the impression being one-half 50 the depth of the article. The punch which goes with this die is constructed in a similar manner to the punch of Figs. 2 to 5, but has its cross section oval without the tongue or projection 24^a. This punch, and also the 55 punch shown in Figs. 2 to 5 is made of sufficient length to permit of considerable grinding off and wearing down, and they may both be, and in practice I contemplate having them, fluted or corrugated on their 60 ends, so that while their cross section contours will be necessarily the same as those of the article, their cutting edges will be corrugated or waved.

I have not illustrated or described specifically 65 the tools employed in forming up the

trimming die as illustrated in Figs. 7 to 11 inclusive, but I may state generally that as hereinbefore stated the metal is forged heated, being swaged up by suitable dies and punches in successive operations in the 70 forms shown respectively in Figs. 9, 10, 11 and 7, in the order given. The value of this method lies in its utilization of the principles of metal flow, so that the metal of the finished product is homogeneous, uniform in 75 grain and texture, without strain or abnormal crystallization, and capable of being uniformly hardened throughout and given a very high finish, resulting in increased efficiency and long life. At the same time, it 80 will be obvious from the description that the cost of production is low and the interchangeability of the individual dies is perfect, because they are mathematically identical in shape and dimensions. 85

Having thus described my invention what I claim and desire to secure by Letters Patent is:

1. The method of producing interchangeable unit trimming dies which consists in 90 first forging a cup with a thin bottom and thickened sides, then further causing the metal to flow into finished shape with inner walls tapering to the bottom, and finally punching out the bottom so as to leave a cut- 95ting edge.

2. The method of producing interchangeable unit trimming dies which consists in first forging a cup with a thin bottom and tapered sides, and then punching out the 100 bottom to form a cutting edge, and finishing the side walls.

3. The method of producing interchangeable unit trimming dies which consists in first forging a cup with thin bottom and tapering sides having their upper edges extended laterally, second swaging up the body so as to cause the metal of the side walls to flow into finished shape with a projecting lateral flange, and finally punching 110 out the bottom to form cutting edges, and at the same operation trimming off the lateral flange and finishing the surface of the sides.

4. The method of producing interchangeable unit trimming dies which consists in first swaging a rough shape into the desired shape of the die, leaving a thin bottom, then by means of a punching die of finished shape punching out the bottom to form a cutting 120 edge, and at the same operation forcing up the metal around the punch and in the die so as to finish the walls with precision.

5. The method of producing interchangeable unit trimming dies which consists in 125 first forging the die with the central opening and cutting edge therein; second treating as by pickling and tumbling to remove the scale left by the hot forging; and third compressing the same in a press between 130

complementary dies under heavy pressure to produce accurate dimensions and shape and a glass finish.

6. The method of producing interchangeable unit trimming dies which consists in first forging the die with the central opening and cutting edge therein; second treating as by pickling and tumbling to remove

the scale left by the hot forging; third compressing the same in a press between complementary dies under heavy pressure to produce accurate dimensions and shape and a glass finish, and finally hardening the die and grinding its base and top or crown. 10

In testimony whereof I affix my signature. 15
FRANK R. STAFFORD.
